Primary Examiner — Bridget L Eland*Assistant Examiner* — Lauren McVey(74) *Attorney, Agent, or Firm* — Dentons US LLP(57) **CLAIM**

We claim the ornamental design for a gateway terminal, as shown and described.

DESCRIPTION

FIG. 1 is a perspective view of a gateway terminal showing our new design;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof;

FIG. 7 is a bottom plan view thereof; and,

FIG. 8 is another perspective view thereof, shown in an upright state.

The dot-dash broken lines immediately adjacent the claim represent the bounds of the claimed design while the evenly spaced broken lines are directed to environment and are for illustrative purposes only; the broken lines form no part of the claimed design.
